UNITED STATES PATENT OFFICE.

FREDERICK I. CANNON, OF BEDFORD, OHIO.

ROOF-COATING APPLICATOR.

1,393,747.

Specification of Letters Patent.

Patented Oct. 18, 1921.

Application filed November 26, 1919. Serial No. 340,909.

To all whom it may concern:

Be it known that I, FREDERICK I. CANNON, a citizen of the United States, residing at Bedford, in the county of Cuyahoga and State of Ohio, have invented certain new and useful Improvements in Roof-Coating Applicators, of which the following is a specification.

This invention relates to a machine that 10 is used for the application of liquid coating, more particularly the application of liquid cement coating to roofs.

Cement is applied to roofs in a more or less thick liquid state, and hardens or sets 15 after it has been applied. It has been the common practice, heretofore, to spread the material over the roof with large brushes manually operated.

The object of the present invention is to 20 provide a machine of simple and durable construction, for conveying, depositing, and uniformly spreading the liquid cement on the roof.

With this object in view, the invention 25 consists in the construction, combination and arrangement of parts as hereinafter described and pointed out definitely in the claims, reference being had to the accompanying drawings which are made part of 30 the specification, similar reference characters being employed to designate corresponding parts.

In said drawings Figure 1 represents an 35 elevation of the improved machine, a portion of the reservoir being broken away.

Fig. 2 is a top plan view of the machine.

Fig. 3 is a top plan of the base member detached.

Fig. 4 is a section on line 4—4 of Fig. 3, 40 showing the door member closed, and Fig. 5 is a similar section showing the door open.

Fig. 6 is an elevation taken at right angles to that shown in Fig. 1.

Fig. 7 is an under side plan view of the 45 machine.

In the present embodiment of the invention 1 represents the shell of a tank or reservoir adapted to contain the cement in a liquid condition. Said reservoir is open at 50 the top and is mounted on a carrier base 2, said base member forming the bottom of the reservoir, an annular flange 2^a being provided for attachment of the shell 1.

The reason for designating the member 2 55 as a carrier member is, that a traction wheel

3 and supporting legs 4 are connected therewith and provide the means for carrying the load.

The traction wheel 3 is keyed or otherwise made fast on a shaft 6, which is mounted 60 in a bracket 7 extending forward from the member 2, and the legs 4 extend from the member 2 diametrically opposite, and at right angles to the wheel 3, said legs being provided with roof bearing elements or runner shoes 4^a, preferably made of leather, adapted to slide on the roof.

The shell 1 is surmounted by, and circumferentially embraced by an annular casting 8 provided with a cross-bar 8^a, and 70 a vertical shaft 9, centrally located in the reservoir, is journaled in said cross-bar and in the base member 2. The shaft 9 carries a series of agitator members 10 and is driven by the action of the traction wheel 3, through 75 intervening mechanism, described as follows: The shaft 6 carries a sprocket wheel 3^a, preferably cast integral with the traction wheel 3, and a sprocket chain 11 coacts with said wheel 3^a and a similar wheel 12 80 carried by a shaft 13. The shaft 13 is mounted in a bracket 8^b that extends from the member 8. A horizontal shaft 14 is mounted in suitable bearings 14^a, and carries two bevel gears 15 and 16. The gear 15 is in mesh with a gear 17 carried by the shaft 13, and the gear 16 is in mesh with a gear 18 which is keyed or otherwise made fast on the vertical shaft 9. It will readily be seen, that the rotation of the agitator 85 members 10 will coincide with the revolution of the traction wheel 3, through the coaction of the mechanism just above described.

Apertures 2^b are provided in the bottom 95 or base member 2 for the discharge of the material, the discharge being controlled by a closure member or door 19 which in the present embodiment is operated in the following described manner. A bar 20 is slidably mounted in horizontal bearings 21, and toggle connection is made between said bar and the door 19, said connection comprising arms 22 which are integral with or rigidly attached to the door 19 and are adapted to 100 extend through the discharge apertures 2^b, said arms being pivotally connected with links 22^a which are in turn pivotally connected with the bar 20 at 20^a. The door 19 is hinged to the member 2 on the interior, 110

as shown at 19^a, and when the bar 20 is forced in, being manipulated by the handle 20^b, the door is raised, oscillating on the hinge pintles 19^a, through the action of the 5 toggle constructed as described. When the bar is drawn in the reverse direction, the coaction of the toggle closes the door over the apertures 2^b.

A spreader is provided, comprising a rotary brush 23 mounted in suitable bearings 10 on the under side of the member 2, parallel with and back of the apertures 2^b. As shown in the drawings the spreader is driven from the shaft 6 through the medium of a sprocket chain 24 coacting with a sprocket wheel 25 carried by said shaft, and a sprocket wheel 26 on the brush shaft. I anticipate, however, dispensing with the brush driving mechanism, as a rotary movement 15 will be imparted to the brush by contact.

A propelling member 27 is connected with the reservoir at 27^a, said member being offset, as shown in Fig. 2, so that the operator in manipulating the machine, travels on the 25 surface of the roof which has not been coated.

From the foregoing description taken in connection with the drawings, the advantages of the invention will be readily apparent, and while I have described the principle of operation of the invention, together with the appliance which is a practical embodiment thereof, I desire to have it understood that the device shown is merely illustrative and that such changes may be made when desired as are within the scope of the invention as set forth in the appended claims.

What I claim and desire to secure by Letters Patent is:

1. In a machine of the character set forth, the combination of a reservoir provided with a discharge aperture in the bottom thereof; a closure member for said aperture; means 45 for operating said closure member for covering and uncovering the aperture; a traction wheel, fixed supporting members connected with said reservoir, extending laterally therefrom and provided with runner shoes; agitators operative in said reservoir; means for driving the agitators, said means being operated by the action of the traction

wheel; and a spreader mounted on the under side of the reservoir.

2. In a machine of the character set forth, 55 the combination of a reservoir provided with a discharge aperture; a base member on which said reservoir is carried; a traction wheel mounted in said base member forward of the reservoir; supporting traction legs provided with roof bearing shoes, extending laterally from said base; means for manually propelling the machine; a hinged closure member for said discharge apertures provided in the base member; 65 means for operating said closure member; agitators operative in the reservoir; means for driving the agitators, said means being operated by the traction wheel; and a spreader mounted on the under side of the 70 reservoir.

3. In a machine of the character set forth, the combination of a reservoir provided with a discharge aperture in the bottom thereof; a closure member for said aperture; means 75 for operating said closure member for covering and uncovering the aperture; a traction wheel mounted in a bracket which is connected with and forward of the reservoir; agitators operative in said reservoir; 80 gear and sprocket mechanism connecting the agitators with the traction wheel, for driving said agitators; and a rotary spreader mounted on the under side of the reservoir.

4. In a machine of the character set forth, 85 the combination of a reservoir provided with a discharge aperture in the bottom thereof; a door for said aperture; means for opening and closing said door; a traction wheel mounted in a bracket forward of the 90 reservoir; traction legs provided with traction bearing elements, extending latterly from the reservoir; a vertical shaft centrally mounted in the reservoir; agitators carried by said shaft; means for driving the shaft, 95 said means being operated by the action of the traction wheel through the medium of coacting gears and sprocket mechanism; a rotary brush mounted on the under side of the reservoir, parallel with the discharge 100 aperture; and means for rotating said brush.

In testimony whereof I affix my signature.

FREDERICK I. CANNON.
